UNITED STATES PATENT OFFICE.

HUGO LOEWENBACH, OF MILWAUKEE, WISCONSIN.

BOWLING ALLEY.

Application filed October 26, 1923. Serial No. 670,872.

To all whom it may concern:

Be it known that I, HUGO LOEWENBACH, a citizen of the United States, and resident of Milwaukee, in the county of Milwaukee and State of Wisconsin, have invented certain new and useful Improvements in Bowling Alleys; and I do hereby declare that the following is a full, clear, and exact description thereof.

10 This invention relates to a new form of game apparatus.

Objects of this invention are to provide a game which takes the general form of a bowling alley, which may be played from either end, which is provided with means for setting up the pins operable by manually manipulable means accessible at either end of the alley, and in which means are provided for maintaining the correct adjustment of each individual pin restoring or setting means.

This invention is an improvement over that disclosed in Patent Number 1,392,586, for game apparatus issued to me October 25 4, 1921, and has the same general objects as those stated in such patent.

Further objects are to provide a bowling alley which is of simple and substantial construction, which is provided with easily produced means for simultaneously setting all of the pins, and which is so constructed that it may be played either primarily as a game of chance or as a game requiring considerable skill.

35 Embodiments of the invention are shown in the accompanying drawing, in which:—

Figure 1 is a plan view of the apparatus.

Figure 2 is a bottom view thereof.

40 Figure 3 is an enlarged sectional view on the line 3—3 of Figure 1.

Figure 4 is a fragmentary plan view showing a further form of the invention.

The device comprises a table-like structure 1 which is in the form of an alleyway. It is provided with side flanges 2 and with the rear end member or flange 3. The forward end of the apparatus is completed by a block 4, which is cutout along a circular

50 line 5, which merges into a straight wall 6. A longitudinally extending partition 7 is spaced from one of the side walls and is provided with a semi-circular portion 8 spaced from the curved face 5 of the block, as

shown in Figure 1, and continued outwardly 55 to form a protecting portion 9 spaced from the wall 6 of the block 4. It will be noted from inspection of Figure 1 that this partition forms a guideway for the balls, which may be thrown or rolled from 60 the rear end of the apparatus, and which, upon leaving the passageway formed between the wall 6 and the portion 9 of the partition will be directed toward the center of the alleyway.

65 The rear portion of the device is recessed, as indicated at 10. The forward end of this recess is tapered, as indicated at 11, to provide substantially a triangular front portion for the cutout part. This cutout 70 part is bridged adjacent its rear portion by a transverse member 12, and a plurality of narrow slats 13, preferably of metal, are arranged in such cutout portion and carried by the body part 1 and by the transverse 75 member 12, as shown in Figures 1 and 3. These slats provide guideways, or spaces, for the several pins 14.

A convenient way of forming the apparatus is to provide a base plate 15 attached to 80 the bottom portion of the body part 1, as shown in Figure 3, and thus serving as a closure for the bottom of the cutout 10. If desired, a plurality of legs 16 may be provided and may be arranged in pairs at 85 the forward and rear ends of the device. Obviously it is within the scope of this invention to provide a stand or legs for supporting the device, although, as shown in the drawings, it is intended to be placed 90 upon the table top.

The bottom plate 15 is provided with a plurality of holes 17 therethrough above each of which is positioned a pin 14. These pins, as shown in Figure 3, are each provided 95 with a cord 18 which extends inwardly through the base thereof and is suitably secured to the pin. These cords 18 extend through the apertures 17 and are attached to an eyelet 19. They are each provided with 100 a spring 20 intermediate their length so as to maintain the correct adjustment for each independent string or cord.

Means are provided for restoring the pins to their upright positions after they have 105 been knocked to a prone position. The means contemplated by this invention includes a lever 21 pivotally carried inter-

mediate its ends by a bracket 22 secured to the under side of the table. This lever carries the eyelet 19 previously described, adjacent one end thereof, and is attached 5 to one end of a spring 23 adjacent its other end, one end of such spring being rigidly attached to the under surface of the table, as shown in Figure 2. A rearwardly extending longitudinal member 24 is secured 10 to one end of the lever 21 and extends beneath the table portion. Its outer end is passed through an aperture in one of the legs 16 and is provided with a manipulating eyelet 25 through which a finger of the 15 operator may be inserted when it is desired to retract member 24 and to thus set the pins in upright position. A second longitudinally extending member 26 is attached to the other end of the lever 21 and is guided 20 at its outer end by passing it through a suitable aperture in the forward leg 16. Its outer end is provided with a manipulating eyelet 27.

It will be seen, therefore, that means have 25 been provided by which the pins may be restored or set from either end of the apparatus, thus permitting the game to be played from either end without requiring the operator to walk to the other end of the 30 device. It is of course to be understood that if desired the bars or rods 24 and 26 may be replaced by flexible members.

In the form shown in Figure 4, the 35 guideway for the balls is provided with a plurality of convolutions 28, 29 and 30, which terminate in a rearwardly and slightly inwardly extending guideway 31. This form of the device provides a circuitous passage for the balls when they are rolled from the rear end of the device and placed in the 40 guideway.

It will be seen, therefore, that a bowling 45 alley has been provided upon which the game may be played from either end. If, for instance, it is played from the rear end, as shown in Figure 1, the balls are placed in the guideway formed between the partition 7 and the side wall 2 and are projected forwardly. These rapidly traveling balls 50 are guided rearwardly by the forward portion of the apparatus and are projected along the alleyway towards the upstanding pins. When the game is played in this manner the rear eyelet 25 is grasped by the operator and withdrawn when it is desired 55 to reset the pins.

Obviously, however, the game may be 60 played from the other end of the alleyway by rolling the balls rearwardly along such alleyway towards such upstanding pins—the balls being placed either between the wall 6 and the portion 9 of the partition, or between the portions 9 and 7 of such partition. When the game is played in this manner 65 considerable skill is required of the players

and the game then becomes substantially similar in its mode of playing to the usual or regulation game of ten-pins.

It is to be noted that the partition 12 and the rear wall 3 form a pocket 32 into which 70 the balls drop after passing the pins. In this manner the balls are retained in an easily accessible position.

It will thus be seen that a bowling alley 75 has been provided, in which two distinct modes of play are possible, and in which the pins may be set simultaneously from either end of the apparatus.

Although the invention has been described in considerable detail, it is to be understood 80 that it may be variously embodied and is therefore to be limited only as claimed.

As shown in Figures 1 and 2 of the drawings, the ball receiving pocket 32 may be provided with a discharge mouth 33, which 85 is controlled by a valve 34. By this mechanism the operator can, if desired, open the valve and permit the balls to drop into any suitable gravity delivery chute by which they will be discharged at the forward end 90 of the apparatus.

I claim:

1. A game comprising an alleyway having a forward and rear end, a plurality of pins located adjacent said rear end and adapted to be knocked into a prone position, a flexible member attached to each pin and adapted to set such pin in upright position when tensioned, a movable member carried by said alleyway and adapted to simultaneously tension all of said flexible members when moved, and manually operable means connected to a portion of said member and extending to one end of said alley, and a second manually operable member connected to another portion of said member and extending to the other end of said alley.

2. A game comprising an elongated body portion having side flanges and a forward and rear end, a plurality of pins mounted adjacent the rear end of said body portion and adapted to be knocked into prone position, said body portion having a plurality of holes therethrough adjacent said pins, cords extending through said holes each having one end attached to a pin and adapted to set said pins in upright position when tensioned, a lever pivoted to the under side of said body portion and having one end connected to all of said cords, tension members connected to opposite ends of said lever and extending in opposite directions to opposite ends of said body portion, and a spring connected to said lever and tending to relieve tension on said cords.

3. A game comprising an elongated body portion having forward and rear ends, a guide extending from said rear end to said forward end and having a rearwardly directed portion for guiding balls towards said rear

portion, a plurality of pins mounted adjacent the rear of said body portion and adapted to be knocked into a prone position, manually operable means for setting said pins 5 in an upright position, said body portion having a ball receiving pocket adjacent its rear end, and a manually operable slide for

controlling the discharge of balls from said pocket.

In testimony that I claim the foregoing 10 I have hereunto set my hand at Milwaukee, in the county of Milwaukee and State of Wisconsin.

HUGO LOEWENBACH.
